(57) CLAIM

The ornamental design for a folding easy carry stadium seat for bleachers, as shown and described.

DESCRIPTION

FIG. 1 is a front elevational view of a folding easy carry stadium seat for bleachers showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines shown in drawings are for the purpose of illustrating stitching on the folding easy carry stadium seat for bleachers and form part of the claimed design.
